UNITED STATES PATENT OFFICE

170,171

AUTOMOBILE

Clifford Brooks Stevens, Milwaukee, Wis.

Application January 30, 1953, Serial No. 23,373

Term of patent 3½ years

(Cl. D14—3)

To all whom it may concern:

Be it known that I, Clifford Brooks Stevens, a citizen of the United States, residing at Milwaukee, in the county of Milwaukee and State of Wisconsin, have invented a new, original, and ornamental Design for an Automobile, of which the following is a specification, reference being had to the accompanying drawings, forming part thereof.

I claim:

The ornamental design for an automobile, as shown.

CLIFFORD BROOKS STEVENS.
